CLAIM

The ornamental design for an X-ray film cassette holder
for use with children, substantially as shown and de-
scribed.

DESCRIPTION

FIG. 1 is a perspective view of an X-ray film cassette
holder for use with children showing our new design.

FIG. 2 is a front elevation view thereof.

FIG. 3 is a side elevation thereof; the opposite side
being a substantial mirror image.

FIG. 4 is a top plan view thereof.

FIG. 5 is a bottom plan view thereof.

FIG. 6 is a rear elevational view thereof.

FIG. 7 is a perspective view of a second embodiment of
an X-Ray Film Cassette Holder for use with children;
FIG. 8 is a perspective view of a third embodiment of
an X-Ray Film Cassette Holder for use with children.

Fig. 1.

Fig. 2.

Fig. 3.

Fig. 4.

Fig. 5.
